UNITED STATES PATENT OFFICE.

ELAM CURE, OF ST. PAUL, MINNESOTA.

FLAGMAN'S SIGNALING KIT.

1,227,587.

Specification of Letters Patent. Patented May 29, 1917.

Application filed August 26, 1916. Serial No. 116,946.

To all whom it may concern:

Be it known that I, ELAM CURE, a citizen of the United States, residing at St. Paul, in the county of Ramsey and State 5 of Minnesota, have invented certain new and useful Improvements in Flagmen's Signaling Kits; and I do hereby declare the following to be a full, clear, and exact description of the invention, such as will enable others skilled in the art to which it 10 appertains to make and use the same.

My invention has for its object to provide a simple and highly efficient flagman's signaling kit; and to such ends, generally 15 stated, the invention consists of the novel devices and combinations of devices hereinafter described and defined in the claims.

For the purpose of signaling trains under various different conditions, flagmen 20 on railway trains are compelled to carry a flag, torpedoes and one or more fusees. My invention combines all of these signaling devices into a common kit, which, in connection with a suitable case, constitute a 25 self-contained unitary device capable of being carried as a single element with any one of the signaling devices available for use whenever required.

In the accompanying drawings which 30 illustrate the invention, like characters indicate like parts throughout the several views.

Referring to the drawings:

Figure 1 is a plan view showing the complete signaling kit;

35 Fig. 2 is an enlarged transverse section on the line 2—2 of Fig. 1; and

Fig. 3 is a plan view showing in detail the rotary flag staff removed from the case.

The case 4 of the signaling kit may be 40 made in a good many different ways, either from metal or wood, but as shown, it is of the latter construction. It is formed with three compartments 5, 6 and 7. The compartment 5 is open at one side and at 45 the bottom of the case and is adapted to contain the signaling flag 8. This signaling flag 8 is detachably secured at its inner edge to a flag staff 9, by means of a screw-equipped clamping bar 10. This flag staff 50 9 is rotatably mounted in the end walls of the compartment 5 and at one outer end, is provided with an operating hand wheel or knob 11, by means of which it may be rotated to wind up the flag on the staff. At 55 its upper edge, the case 4 is provided with a hand piece 12, by means of which it may be

carried. Said hand piece 12 also affords convenient means for holding the case and using the latter as a flag support when the flag is uncoiled and used to signal a train. 60

The compartments 6 and 7 are each long enough to contain two axially aligned fusees 13. These fusees, as well known, are of cylindrical form and usually provided with projecting spikes 14, by means of which 65 they may be stuck either into the ground or into a tie. These fusees 13 are held within the compartments 5 and 6, preferably by spring yokes 15 that are passed through perforations 16 formed in the partition between the compartments 5 and 6. These yokes 15 are made of spring metal and their ends are turned together and preferably arranged to bear upon the upper surface of the said partition. The fusees 70 are thus held at their central portions in such manner that one may be thrown out endwise from its holding compartment and from the holding yoke 15.

The torpedoes 17 are provided with the 80 customary spring prongs 18, and these prongs are projected into the compartments 6 and 7 and sprung over the fusees 13. Any one of the torpedoes can be removed by pulling it directly outward, but preferably, 85 they are removed by sliding the outermost laterally outward and off from the outer ends of the fusee to which they are normally applied.

In the above described arrangement it is 90 evident that the fusees directly serve as supports for the torpedoes, and that either a torpedo or a fusee may be readily removed from the case, at will, or the flag used when desired. 95

What I claim is:

1. A casing for a flagman's kit constructed with a flag containing compartment open at one side thereof and parallel therewith, with laterally spaced longitudinally extended fusee containing compartments separated by a partition having perforations through which spring yokes may be passed to secure fusees in position therein. 100

2. A flagman's kit comprising a casing 105 having fusee containing compartments separated by a partition, fusees contained in said compartments, and spring yokes passed through perforations in said partition and embracing said fusees and holding the same 110 therein.

3. A flagman's kit comprising a casing

having fusee containing compartments separated by a partition, fusees contained in said compartments, spring yokes passed through perforations in said partition and embracing said fusees and holding the same therein, and torpedoes having spring prongs embracing said fusees.

In testimony whereof I affix my signature in presence of two witnesses.

ELAM CURE.
